FURNACE STRUCTURE

Clarence Lynn, Forest Hills, Pa., assignor to Westinghouse Electric Corporation, East Pittsburgh, Pa., a corporation of Pennsylvania

Application February 22, 1945, Serial No. 579,242

6 Claims. (Cl. 263—40)

1

This invention relates to gas-tight inner hoods or covers for use in relatively large furnaces of the bell type. Hoods of this kind have a charge-enclosing section within the heating chamber of the furnace for enclosing a charge or work so that the charge can be enveloped, during heating, by a protective or controlled special atmosphere, and a sealing section or skirt which extends from the heated enclosing section to a much cooler zone where a good gas seal can be provided. In some bell-furnace designs, the skirt extends outwardly substantially horizontally from the enclosing section and the heating bell of the furnace sits thereon, but other designs exist.

The enclosing section of the hood is commonly made of expensive heat-resisting alloy because it is subjected to high heat which must pass through it to the charge. The sealing or skirt portion can be made of steel, which is considerably less costly. For large furnaces, the hoods are generally fabricated of several metal parts welded together. For an ideal hood, the welds should not crack or break, and parts of the hood should not warp excessively during repeated heatings and coolings such as attend the normal use of a bell furnace. Warpage is particularly obnoxious in the part of the skirt which extends from the heated charge-enclosing section inside the furnace to the seal which is usually outside the heating zone, such part having a high temperature gradient therewith.

It is an object of my invention to provide an improved furnace hood of a general type described, having features conducive to a long useful life.

It is a further object of my invention to provide an improved furnace hood of a type described in which damage to welds and warpage of parts are limited.

Features, objects and innovations of my invention, in addition to the foregoing, will be discernible from the following description of a preferred embodiment which is to be taken in conjunction with the accompanying drawings.

In the drawings,

Figure 1 is a vertical sectional view of a circular bell furnace embodying my improved hood;

Fig. 2 is an enlarged horizontal sectional view substantially along the lines II—II of Fig. 1; and Figs. 3 and 4 are partial views in section sub-

2

stantially along the lines III—III and IV—IV of Fig. 2; respectively.

The circular bell furnace of the embodiment shown comprises a stationary base, indicated in its entirety by the reference numeral 2, which supports a removable heating bell 4 surrounding most of a removable metallic hood 6.

The base 2 comprises a bottom gas-impermeable metal plate member 8 terminating in a peripheral outer trough 10 adapted to contain a sealing material, usually liquid. The plate member 8 carries a non-metallic stepped refractory charge-supporting bed comprised of an inner raised hearth 12, and an outer annular-like portion 14 on which the heating bell 4 can be carried.

The hood 6 comprises a central cylindrical charge-enclosing section 16 having a closing top member 18. The charge-enclosing section 16 is fabricated in any suitable manner, preferably of a heat-resistant alloy, and terminates in an open bottom provided with a circular edge 20. The hood 6 also comprises a skirt section 22 comprised of a flat annular member 24 and a depending cylinder 26 which fits into the trough 10. The annular member 24 has an inner edge 28 having a diameter larger than that of the edge 20 of the charge-enclosing section 16.

The skirt section 22 and the charge-enclosing section 16 of the hood 6 are jointed by an annular-like curved hood section 30 which may be considered as a surface of revolution of the cross-section shown in Figs. 1 and 3 about the center axis of the furnace. It comprises an upstanding leg or part 32 which rests against the outer surface of the border portion of the charge-enclosing section 16, contiguous to the edge 20, and a substantially horizontal leg or part 34 which rests on the surface of the border portion of the skirt section 22, contiguous to the edge 28. A curved part between the aforementioned substantially straight legs 32 and 34 completes the curved annular-like section 30. This curved annular-like section is fluid-tightly welded to the charge-enclosing section and to the skirt section of the hood. The annular-like section 30 is preferably made of a heat-resistant alloy which may be the same as that of which the charge-enclosing section 16 is made.

The hood 6 comprises a water jacket 36 formed in cooperation with an inner part of the annular

member 24, and all except the uppermost portion of the curved annular-like hood section 30. The jacket comprises a flat annular top plate 38 and an outer narrow upstanding curved bar 40. The bar 40 and plate 38 have abutting edges welded together to form an annular member which is angular in cross section. This angular member has its edges welded, respectively, to the annular-like section 30 and to the flat annular member 24.

In order to provide a clear path for circulating water around the water jacket 36, the latter also comprises a small extension 42 which extends outwardly from the water jacket and is formed of a flat top plate 44 and spaced outer bars 46 water-tightly secured to each other and to the annular member 24 and associated parts of the water jacket. A central inner bar 48, which extends to the annular-like section 30, divides the extension 42 into a water inlet compartment 50 and a water outlet compartment 52. Water is fed to the inlet compartment 50 through a pipe 54, and is removed from the outlet compartment 52 through a pipe 56. The pipes pass fluid-tightly through suitable holes in the skirt section 22, and through the stationary base 2. Suitable hoses and connections continuously feed and remove water to and from the pipes 54 and 56.

The heating bell 4 comprises a metal outer casing 60 and a lower frame plate 62 which supports refractory tile 64. The refractory tile carries electrical heating units 66 in any suitable manner. The frame plate 62 sits on a narrow annular ring 68, which sits on the outer edge portion of the flat annular member 24 of the skirt section 22.

An indication of the size of an actual installation along the lines of the embodiment shown can be obtained from the following dimensions: outside diameter of the charge-enclosing section 16, 52 inches; height, about 165 inches; inner and outer diameters of the flat annular member 24, substantially 54½ and 85 inches, respectively; outer diameter of water jacket 36, about 61 inches, the jacket extension 42 extending approximately 8 inches radially outwardly therefrom, and being about 6 inches wide and 1¾ inches high.

A hood of a type herein described has been found more satisfactory with respect to the occurrence of warpage and cracks and failure of welds than prior similar hoods.

While I have described my invention with respect to a preferred form thereof associated with a bell furnace, it is obvious that the teachings of my invention have broader application.

I claim as my invention:

1. A fabricated circular gas-tight hood of a type described, comprising a cylindrical upstanding charge-enclosing section, an annular substantially horizontal skirt section around and spaced from a bottom portion of said charge-enclosing section, an annular-like curved connection section having an upstanding part lapping said bottom portion of said charge-enclosing section and having an outwardly directed part lapping said skirt section, members cooperating with the inner portion of said skirt section and with said outwardly directed part of said connection section, for forming a low water jacket therewith, said water jacket extending across a minor part only of the width of said skirt section, and water inlet and outlet means for said water jacket, passing through the bottom of said skirt section.

2. A fabricated circular gas-tight hood of a type described, comprising a cylindrical upstanding charge-enclosing section, an annular substantially horizontal skirt section around and spaced from a bottom portion of said charge-enclosing section, an annular-like curved connection section having an upstanding part lapping said bottom portion of said charge-enclosing section and having an outwardly directed part lapping said skirt section, members cooper-

ating with the inner portion of said skirt section and with said outwardly directed part of said connection section, for forming a low water jacket therewith, said water jacket extending across a minor part only of the width of said skirt section, the top of said water jacket being below the top of said connection section, and water inlet and outlet means for said water jacket, passing through the bottom of said skirt section.

3. A fabricated gas-tight hood of a type described, comprising an upstanding charge-enclosing section, a substantially horizontal skirt section having an inner edge around and spaced from, but near, a bottom portion of said charge-enclosing section, a connection section coextensive with and overlapping said skirt section and said bottom portion of said charge-enclosing section, and wall members cooperating with said connection section for forming a relatively low water jacket extending across a minor part only of the width of said skirt section.

4. A fabricated gas-tight hood of a type described, comprising an upstanding charge-enclosing section, a substantially horizontal skirt section having an inner edge around, and spaced from, a bottom portion of said charge-enclosing section, a connection section co-extensive with and overlapping said skirt section and said bottom portion of said charge-enclosing section, wall members cooperating with said connection section for forming a relatively low water jacket extending across a minor part only of the width of said skirt section, and water inlet and outlet piping for said water jacket, passing through said skirt at a distance inwardly spaced from the outer edge of said skirt section.

5. In a bell furnace, the combination of an outer heating bell having walls carrying heating elements, and an inner gas-tight metal hood of a type described spaced from said walls to provide a heating space between the bell and the hood, said heating elements being exposed in said heating space, said hood having an upright charge-enclosing section and a horizontal annular skirt section joined together, said hood being further characterized by having a wall-means providing a water-jacket at the joint of said upright charge-enclosing jacket and said annular section, said water-jacket having a top wall exposed in said heating space and bounding a bottom part of it, said water-jacket occupying an inner annular part of said skirt, the outer annular part of said skirt being under said walls of said bell, and water inlet and outlet means to said water-jacket.

6. In a bell furnace, the combination of an outer heating bell having walls carrying heating elements, and an inner gas-tight metal hood of a type described spaced from said walls to provide a heating space between the bell and the hood, said heating elements being exposed in said heating space, said hood having an upright charge-enclosing section and a horizontal annular skirt section, an annular section which is curved in an axial plane so as to provide annular

legs, said legs overlapping a bottom part of said upright charge-enclosing section and an inner part of said annular skirt, a low upright cylindrical wall secured to said skirt outwardly of said legs, a top wall secured to said upright wall and to said charge-enclosing section, whereby to form a water-cooling chamber for the joint between said skirt and said charge-enclosing section, said skirt extending radially outwardly beyond said upright wall to provide an annular part under 5 said walls of said bell for supporting said bell, said top wall of said water-cooling chamber being exposed in said heating space.
